UNITED STATES PATENT OFFICE.

ROY E. GEARHART, OWEN D. STEWART, AND LOUIS A. HECKEL, OF KANSAS CITY,
MISSOURI.

DESIGN FOR A VACUUM-CLOTHES-CLEANER CASING.

Application filed July 5, 1921. Serial No. 482,598. Term of patent 3½ years.

To all whom it may concern:

Be it known that we, ROY E. GEARHART, OWEN D. STEWART, and LOUIS A. HECKEL, citizens of the United States, residing at Kansas City, Jackson County, Missouri, have invented a new, original, and ornamental Design for a Vacuum-Clothes-Cleaner Casing, of which the following is a specification, reference being had to the accompanying drawing, forming a part thereof.

In the drawing:

Figure 1 is a side elevation of a vacuum clothes cleaner casing constituting our new design.

Figure 2 is a top view of the same.

Figure 3 is a bottom view of the same.

We claim:

The ornamental design for a vacuum clothes cleaner casing as shown.

ROY E. GEARHART,
OWEN D. STEWART,
LOUIS A. HECKEL.
